UNITED STATES PATENT OFFICE.

FRANK HOLBROOK, OF LYNN, MASSACHUSETTS, ASSIGNOR TO HAMEL SHOE MACHINERY COMPANY, OF LYNN, MASSACHUSETTS, A CORPORATION OF MASSACHUSETTS.

BURNISHING-MACHINE.

1,113,216.

Specification of Letters Patent.

Patented Oct. 13, 1914.

Application filed October 12, 1912. Serial No. 725,401.

To all whom it may concern:

Be it known that I, FRANK HOLBROOK, a citizen of the United States, residing at Lynn, county of Essex, State of Massachusetts, have invented a certain new and useful Improvement in Burnishing-Machines, of which the following is a specification, reference being had therein to the accompanying drawings.

10 My invention relates to heel burnishing machines of the class in which the wax or burnishing agent is applied hot to the heel surfaces, by means of a revolving wheel.

The object of my invention is to produce 15 an effective and economical device for the above purpose.

It consists in certain novel features of construction and arrangement, more particularly of the wax pot or container, and the 20 mechanism employed in the wax pot or container for transferring the hot liquid wax in proper quantities from the pot to the periphery of the burnishing wheel, all as hereinafter more fully set forth in the following 25 description of a machine embodying my invention and illustrated in the accompanying drawings forming a part hereof.

The novel features of my invention are 30 pointed out and clearly defined in the claims at the close of the specification.

In the drawings, Figure 1 is an end elevation showing the essential portions of a machine embodying my invention. Fig. 2 is a detail partly in section showing a burnishing wheel, the wax pot or container and the device for transferring the wax to the periphery of the burnishing wheel. Fig. 3 is a plan view of the wax transferring and applying device. Fig. 4 is a detail in perspective of the wax applying segment. Figs. 5 and 6 are details showing a modified form of wax applying segment.

Having reference to the drawings, the frame of the machine is shown at A, and is 45 of common form and the ordinary construction. It is provided with a shaft B which is driven in the usual and ordinary manner. On a free end of the shaft B the burnishing wheel is mounted as shown in Fig. 1. This 50 wheel may be of any well known and ordinary form.

The burnishing agent is supplied to the wheel from a wax pot or container 10 located directly beneath the burnishing wheel 55 and preferably of the shape shown in Figs.

1, 2 and 3. This container is mounted upon the frame of the machine by means of a lateral lug or extension 11, on the back side of the pot or container 10 as shown in Fig. 1, which is provided with an adjusting slot 60 12 through which a bolt 13 passes to secure the extension 11 to the horizontal portion 14 of a bracket 15 which latter is also provided with an adjusting slot 16 through which two bolts 17 and 18 pass into the upright frame 65 of the machine. By this arrangement of bolts and slots the container is not only vertically adjustable, but is also laterally adjustable, as will be clear. The container 10 has a slanting floor 19 and a well 20. It is 70 also provided with a transverse partition 21, having a hole 22 near the base thereof. This partition 21 forms a compartment rearwardly thereof *i. e.* to the left as shown in Figs. 1 and 2 in which a piece of solid wax 75 may be placed which as it melts under the influence of the heat applied underneath the container from the burner 23, runs through the opening 22 into the well 20 so that a proper supply of wax is maintained in the 80 well. The wax-transferring and applying mechanism comprises a cross-bar 24 which is pivoted as shown in Figs. 2 and 3 between the side walls of the container at the right hand end as shown in Fig. 3. A sleeve 25 85 is secured centrally of the cross-bar and projects at right angles thereto as shown in Fig. 3. The sleeve 25 receives the cylindrical shank 26, see Fig. 2, of the yoke-shaped support 27, said shank being retained in said 90 sleeve 25 by means of a set screw 28 which projects into an annular groove 29 in the said shank, thus permitting the shank to tilt or rock for the purposes hereinafter set forth.

At the forward end of the yoke 27 is pivoted a segment 30 by means of which the liquid wax is transferred from the well and applied to the periphery of the burnishing wheel. Outside of the wax pot or container is a projecting handle or lever 31, which is secured by means of a set screw 32 to the projecting trunnion of the cross-bar 24, as will be clear from Figs. 1, 2 and 3. The segment 30 is normally in the position 105 indicated by dotted lines as shown in Fig. 1. The lower edge of the segment is weighted, as will be clear from the detail in Figs. 4 and 6, in which the lower wall 33 is shown as of greater thickness than the up-

95

100 105 110

per wall 34. As the segment is pivoted in a yoke-shaped frame 27 the weighted lower edge will drop down and the segment will assume the position shown in Fig. 1, which 5 might be called a vertical position. It is prevented from swinging past the vertical by means of a stop pin 35 set in the end thereof, which stop pin contacts with the arm of the yoke 27, as will be clear from 10 Fig. 3. When the device is in its normal position shown in Fig. 1 the upper portion thereof is above the level of the wax, the latter level being indicated by dotted line 36, Fig. 1, and the full line 37, Fig. 2. The 15 portion of this device which is within the wax pot or container is only slightly heavier than the handle or tilting lever 31, so that a very slight touch from the finger of the operator will serve to raise the segment 20 30, forcing it into contact with the revolving burnishing wheel. As the segment is free to oscillate it will travel in contact with the periphery of the burnishing wheel until it assumes the position shown 25 in Fig. 2, at which time the segment contacts with the floor of the wax pot and then it will again drop clear of the burnishing wheel and back into the well 20 of the container.

30 The travel of the burnishing wheel is so rapid that when the handle 31 is touched and the segment 30 is brought into contact with the revolving wheel, it will remain in contact long enough to move the segment 35 into the position shown in Fig. 2. There will thus be applied to the periphery of the burnishing wheel a transverse band of fresh wax. This wax is picked up by the burnishing wheel without causing any of the wax to 40 throw or spatter and one application of the wax by the segment is sufficient for a heel. There is therefore very great economy in the use of the wax or burnishing agent. It is to be noted that in the position shown 45 in Fig. 2 one edge of the segment is in contact with the curved portion 38 of the floor of the wax pot. This portion of the floor is formed in this curved manner in order to accommodate this edge of the segment when 50 the segment has moved over by contact with the revolving burnishing wheel. From the construction heretofore described in which the yoke 27 supporting the segment is provided with a circular shank 26 which is 55 mounted in a sleeve 25 it will be clear that the yoke 27, and consequently the segment, may tilt transversely of the periphery of the wheel. This is important in order that the wax applying segment may accommodate 60 itself fully to the periphery of the wheel and come fully in contact therewith transversely thereof. When the burnishing wheel employed is convex in cross section, as shown, the wax applying segment should 65 preferably be concaved, as shown in Figs.

3 and 4, to correspond with the convexity of the periphery of the burnishing wheel. This insures an even application of the wax to the wheel. If a flat faced burnishing wheel is employed, such as is used for burnishing flat-sided or so-called military heels, then the periphery of the segment should be flat; that is, it should not be concaved as shown in Figs. 3 and 4, but simply a straight line from end to end, corresponding with 75 the straight or flat periphery of the burnishing wheel. It is however frequently desired to change a burnishing wheel over for work of a different kind. It is not, however, feasible to remove the segment 30 when 80 such a change is made in the burnishing wheel and substitute a new segment having a face corresponding with the face of the wheel with which it is to be used. This removal of the segment is not practicable, because it is very hot by reason of its being 85 immersed normally in very hot wax. To avoid the necessity of removing the wax transferring segment, I make one-half of the periphery of the segment concaved and 90 the remaining half flat. See Figs. 5 and 6. By this means one and the same segment will coöperate with either a convex or a flat faced burnishing wheel. The roll of the segment in contact with the wheel is such 95 that the burnishing wheel makes contact when the handle 31 is tilted with both the concave and the flat portions of the face of the segment, and the contact is sufficient whether the polishing wheel be convex or 100 flat faced to supply the necessary quantity of wax to the periphery of the wheel. It is therefore unnecessary to change the wax transferring segment if a change is made in the burnishing wheel. 105

In the operation of my machine, the operator standing in the usual position, touches the tilting lever 31, which causes the transfer and application to the burnishing wheel of a proper amount of wax for burnishing 110 one heel. The heel is applied to the polishing wheel and is quickly coated and polished. He then presents the heel to the beader not shown where it is beaded in the well known manner, and completes the operation by polishing the heel on the brush wheel F. 115

What I claim is:

1. In a burnishing machine, the combination with a rotating burnishing wheel of a pivoted segment having a limited substantially arc-shaped wax applying surface, said segment being rotatable for a partial revolution by contact with the burnishing wheel, and a pivoted support under the control of the operator, said segment being pivotally mounted on said support whereby it is movable into and out of contact with the burnishing wheel to make its partial revolution. 120 125 130

2. In a burnishing machine, a burnishing wheel, a wax-transferrer pivoted to be capable of oscillation and weighted on one side, and means for bringing the wax-transferrer into contact with the burnishing wheel.
3. In a burnishing machine, the combination with a burnishing wheel of a heated container for the burnishing agent, a transferrer comprising a journaled segment weighted on one side, a pivoted support therefor, and means for tilting said support on its pivot to move the transferrer into contact with the periphery of the burnishing wheel.
4. In a burnishing machine, the combination with a burnishing wheel, of a heated container for the burnishing agent, a trans-
- ferrer comprising a journaled segment, a pivoted support therefor comprising two separate parts, one part having a shank on 20 which is an annular groove, the other part having a sleeve within which said shank is received, a pin in said sleeve to engage said annular groove, means for securing said pin in said groove, and means for tilting 25 said support on its pivot to move the transferrer into contact with the periphery of the burnishing wheel.

In testimony whereof I affix my signature, in presence of two witnesses.

FRANK HOLBROOK.
